COMBINED BIRD FEEDER AND WASTE FOOD DRIER

Idolee Simpson, 7631 Jerome Ave.,
Maplewood, Mo. 63143

Filed June 10, 1970, Ser. No. 23,427

Term of patent 7 years

Int. Cl. D30—03

U.S. Cl. D30—14

Fig. 1

Fig. 2

FIG. 1 is a top perspective view of a combined bird feeder and waste food drier showing my new design, the screen therein fragmentarily shown to reveal the appearance of the bottom interior, and the tubular stand fragmentarily shown to indicate variable length; and

FIG. 2 is a section taken in the direction of line 2—2 on FIG. 1.

I claim:

The ornamental design for a combined bird feeder and waste food drier, substantially as shown and described.
